Inventor:

Adolph Pfeiffer.

By: *Adolph Pfeiffer*

UNITED STATES PATENT OFFICE.

ADOLPH PFEIFFER, OF CHICAGO, ILLINOIS.

CLASP.

1,396,941.

Specification of Letters Patent. Patented Nov. 15, 1921.

Application filed August 23, 1920. Serial No. 405,369.

To all whom it may concern:

Be it known that I, ADOLPH PFEIFFER, subject of the present Government of Russia, residing at Chicago, in the county of Cook 5 and State of Illinois, have invented certain new and useful Improvements in Clasps, of which the following is a specification.

This invention relates to improvements in 10 clasps, particularly adapted, though not necessarily limited in its use as a suspender clasp and one of the objects of the invention is to provide an improved clasp of this character which will be effective and efficient in operation and which will securely 15 hold the article to which it is to be connected.

A further object is to provide an improved 20 clasp of this character having means for locking or securing the fastening lever or member against accidental movement about its pivot.

To the attainment of these ends and the accomplishment of other new and useful objects as will appear, the invention consists 25 in the features of novelty in substantially the construction, combination and arrangement of the several parts, hereinafter more fully described and claimed and shown in the accompanying drawing illustrating this 30 invention and in which—

Figure 1 is a face view of one form of the invention.

Fig. 2 is a sectional view taken on line 2—2 Fig. 1.

Fig. 3 is a view similar to Fig. 1 showing the clasp in an open position.

Fig. 4 is a side elevation of Fig. 3.

Fig. 5 is a view similar to Fig. 1 of another form of the invention.

Fig. 6 is a sectional view taken on line 6—6 Fig. 5.

Fig. 7 is a view similar to Fig. 5 showing the clasp in an open position.

Fig. 8 is a side elevation of Fig. 7.

Referring more particularly to the drawing the clasp consists of a body portion constructed of any suitable sheet material such as metal bent back upon itself to form the spaced portion 10 and 11 and in order to 45 hold the parts in such position and to prevent the members 10 and 11 from spreading or being contracted, a suitable fastening device 12 may be provided. The portion 10 of the body, in the form of the invention shown

50 in Figs. 1 to 4, is provided with any desired number of elongated apertures or openings

13 therethrough and projecting beyond the portion 10 are spaced ears 14, which are preferably arranged adjacent one end of the portion 10.

Pivottally mounted to the ears 14 is a lever or element 15 which is provided with prongs or teeth 16 adapted to be projected through the openings 13 when the lever 15 is moved about its pivot in such a direction as to 60 cause the lever 15 to rest against or stand in close proximity to the portion 10 of the body. Connected with the lever 15 at any desired point preferably adjacent its free end is a catch 17 of any desired construction. This catch is adapted, when the lever 15 is moved into the position shown in Figs. 1 and 2, to enter an opening 18 in the portion 10 of the body and to coöperate with one of the walls of the opening 18 after 65 70 yieldingly locking the lever 15 against movement about its pivot.

If desired, the free end of the portion 11 of the body may be bent back upon itself as at 19 to form a shoulder with which the 75 ends of the prongs or teeth 16 coöperate.

In use the clasp may be connected to a suspender, a portion of which is designated as at 20 or to any other suitable portion of a garment, in any desired manner such as by 80 means of a link 21 which passes through the opening 22 formed between the portions 10 and 11 of the body and the fastening device 12. The lever 15 is moved into the position shown in Figs. 3 and 4 and the garment or 85 element to which the clasp is to be attached is inserted between the portions 10 and 11 of the body after which the lever 15 is moved about its pivot into the position shown in Figs. 1 and 2 so that the prongs 16, will 90 95 either penetrate or be forced against the surface of the inserted element to force the latter against the portion 11 of the body for securely holding the element, the catch 17 entering the opening 18 and locking the lever 15 against movement. The shoulder 19 formed on the end of the portion 11 coöperates with the prongs 16 to frictionally hold the element against displacement with respect to the clasp.

In the form of the invention shown in Figs. 5 to 8 the portion 10 of the body is provided with a portion or opening 23 which is of a considerable area and an opening 24 is also provided in the portion 10 and may, if desired, communicate with the opening 23. The lever 15 is provided with a series of

toothed members 25 secured thereto in any desired manner such as by means of fastening devices 26 or, if desired, these teeth 25 may be welded to the lever 15 or may be formed integral therewith.

The inner face of the portion 11 of the body is provided with a series of corrugations or serrations adapted to coöperate with the corrugated or serrated edges 28 of the teeth 25.

This form of the clasp is used in the same manner as the form shown in Figs. 1 to 4 and when the lever 15 is moved into the position shown in Fig. 6 the material will be frictionally gripped between the serrated faces 28 of the teeth 25 and the serrations or corrugations 27 on the portion 11 of the body.

While the preferred form of the invention has herein been shown and described, it is to be understood that various changes may be made in the details of construction and in the combination and arrangement of the several parts, within the scope of the claims without departing from the spirit of this invention.

What is claimed as new is:

A clasp embodying a substantially U

shaped body portion, a reinforcing fastening device connected with the members of the U to extend across the space therebetween, said fastening device being spaced from the bend of the body portion to form a suspension eye or opening, portions of one of the members of the body being deflected to form laterally projecting ears, the last said member having an opening therethrough, a lever pivotally mounted between the said ears, a plurality of spaced toothed members carried by and projecting from the lever and extending transversely across the lever, said toothed members being adapted to project through the said opening to coöperate with the other member of the body portion, corrugations extending transversely of the last recited member and with which corrugations the toothed members coöperate, and a catch carried by the said lever and adapted to coöperate with an edge of one of the members of the body portion for yieldingly locking the lever against movement with respect to the said body.

In testimony whereof I have signed my name to this specification, on this 21st day of August, A. D. 1920.

ADOLPH PFEIFFER.
